UNITED STATES PATENT OFFICE.

WILLIAM FRIBERG, OF PORTLAND, OREGON.

METALLIC SLEEPER.

No. 834,288.

Specification of Letters Patent.

Patented Oct. 30, 1906.

Application filed May 8, 1905. Serial No. 259,412.

To all whom it may concern:

Be it known that I, WILLIAM FRIBERG, a citizen of the United States, residing at Portland, in the county of Multnomah and State of Oregon, have invented certain new and useful Improvements in Metallic Sleepers; and I do hereby declare the following to be a full, clear, and exact description of the invention, such as will enable others skilled in the art to which it appertains to make and use the same.

This invention relates to improvements in metallic sleepers, and particularly to that class of sleepers which may be used as metallic securing means for flooring when placed upon composition or other fireproof floor-supports.

The invention comprises certain novel constructions, combinations, and arrangements of parts, as will be hereinafter fully described and claimed.

In the accompanying drawings, Figure 1 is a vertical sectional view through a portion of a floor and ceiling of a building, showing the supporting-beams, the concrete or similar filling with the flooring resting upon the surface thereof, and my improved flooring-securing means embedded in the cement. Fig. 2 is an enlarged detail view showing one form of the flooring-securing means. Fig. 3 is a similar detail view showing the securing means made in a slightly-different manner. Fig. 4 is also a similar view illustrating a still different manner of shaping the securing means. Fig. 5 is a detail sectional view through a portion of a floor, showing one of the anchoring devices. Fig. 6 is a detail sectional view through a portion of a floor, showing short sections of anchoring devices.

I am aware that means have been employed for securing flooring to the floor-supporting beams of buildings or similar structures; but in the present invention I contemplate using a metallic means for securing and anchoring the flooring in place upon a cement or other composition support, the said securing and anchoring means not forming any part of the weight-sustaining structure of the floor.

In the accompanying drawings I have illustrated the preferred forms of my improved floor-securing sleepers and will first refer to the forms shown in Figs. 1 and 2. In these views, 1 indicates a metallic sleeper formed of a corrugated piece of material, the corrugations being arranged to provide a

double web 2 for the sleeper. The upper and lower edges of the sleeper are turned to one side to form flanges, as at 3 and 4. As shown in these figures, the two portions of the webs and the flanges may be united at 5, one of the flange edges, as at 5. When forming the sleeper in this shape, the said sleeper can be made of a single piece of material and bent to form the lower flange 4, from which rises the corrugated double central portion or web 2, the upper edges thereof being turned to one side in opposite directions to form the upper flanges 3. The web portions are preferably secured and held with respect to each other by bolts or rivets 6, passed through the same at suitable intervals. The said rivets are preferably so secured in place that some resiliency or yielding quality is left in the web portion of the sleeper. The space between the portions of the web 2 is adapted to receive the greater portion of securing nails or pins 7, which are driven through the flooring 8 and between the double walls of the web 2, as clearly illustrated in Fig. 2 of the drawings.

In using my improved securing means or sleeper for fastening flooring in place in a fire-proof structure the flooring is arranged as usual, being supported upon the lower flanges 9 of floor beams or girders 10. In the event of tiles being employed in constructing the flooring the said tiles, as 11, (shown in Fig. 1,) are usually arched between the lower portions of the beams 10. A mixture of concrete or other suitable material is then placed upon the arched tiling, as shown at 12, the said mixture being built up above the top edges of the beams 10. The sleepers 1 are then set in position a suitable distance apart and the filling of concrete, cinders, or other material is packed around them until the fire-proof material is built up to the surface of the flooring 8. The filling of concrete or similar material thus engages the flanges of the sleepers and the outer surface of the web portions, so as to firmly anchor the said sleepers in position, as shown in Fig. 1. The sleepers are set in the material so that their upper flanges 3 will be flush with the upper surface of the concrete material. The flooring is then laid upon the concrete or cement filling and the sleepers, and the securing-nails 7 are driven through the flooring so as to force their way between the opposing walls of the sleeper-webs 2. The nails or other securing means

- 7 must force their way between the walls of the webs and are thus tightly gripped by the said walls, so as to accomplish a firm holding and anchoring of the flooring in position. 5 This gripping action is enhanced by forming the walls of the web 2 of corrugated material, as shown in Fig. 2, and especially when the material is comparatively thin and possessed of some yielding or springing qualities.
- 10 The entrance of the nails between the portions of the web 2 is facilitated by the formation of the said webs at their upper edge. The webs are shaped to form inclined flaring faces, as at 13 and 14. A comparatively 15 wide entrance to the space between the portions of the web is afforded and the points of the nails are readily guided to their position within the body portion of the sleeper.
- Instead of making the sleepers of a single 20 piece of material, as shown in Figs. 1 and 2, it will be evident that the sleepers may be formed of two portions 15 and 16, as shown in Figs. 3 and 4. In this event, however, the parts are secured together by bolts or rivets; 25 but a sufficient space is left between the web portions to receive and hold the nails. As shown in Fig. 3, the flanges of the sleeper may be strengthened by turning their outer edges outwardly and then folding them back again 30 upon themselves, as indicated at 17 and 18. In this manner comparatively stiff and strong flanges are formed upon the sleepers and a good hold is afforded the concrete or other mixture upon the said sleepers and their flanges. I do not wish, however, to limit myself to the use of the double flanges, for, as 35 shown in Fig. 4, the sleepers may be formed of two sections 19 and 20, the upper and lower edges of which are merely turned outwardly 40 to form flanges 21 and 22.
- Since the sleepers are only used as an anchoring means for the flooring and not as a supporting means for the material of the floor or ceiling, it is not necessary that the flanges 45 be made of great strength, for there is no compression or suspension strain upon the same. The said sleepers are embedded in the material of the floor-support not for the purpose of sustaining its weight, but for the purpose of 50 binding the wooden flooring to the surface of the cement or other fireproof mixture. Of course it will be understood that I contemplate using any shaped web and flanges which will form a sleeper of the general type above described, all within the spirit of the invention. I prefer, however, the form of sleeper described having the double corrugated walls and the laterally-extending flanges capable of being embedded in a cement, concrete, 55 or other mixture, since a resilient spring-retaining means is thus afforded for gripping and holding the nails of the flooring in position. When forming the sleepers of separate pieces, as shown in Fig. 3, the inwardly-folded edges of the sections may be made to
- abut against each other, especially at the lower flange 18, for strengthening the structure, and the upper folded portions of the flanges can be so bent as to provide converging inlet-openings, as at 23, for receiving the 70 ends of the nails.
- An important advantage in employing securing-sleepers or anchoring means of this character accrues from the fact that the said sleepers may be arranged to extend in any 75 direction with relation to the floor-supporting beams—that is to say, they can extend parallel with said beams or at right angles thereto or oblique thereto, as found most desirable for the placing of the flooring. 80
- The great utility of this invention of course lies in the fact that metal may be employed for forming the sleepers instead of wood, wood being subject to deterioration, and especially to dry rot when incased in cement, 85 concrete, or like mixtures. This difficulty is not experienced in the employment of metallic anchorage for the flooring, and the securing means for holding the flooring in position is thus practically indestructible. 90
- While the sleepers or anchoring devices 1 may be made in considerable lengths, so as to extend, for instance, entirely across a room, it will be evident that the said sleepers or anchoring devices may be made in short sections placed at intervals, as illustrated in Fig. 95 5. In said figure a series of comparatively short anchoring-sections 24 are illustrated, which are shown as placed in alinement at given intervals. The construction of the sections is the same as when the anchoring devices are made in the form of long or continuous sleepers.
- It will be understood, of course, that the sectional sleepers may be arranged in offset 105 relations to each other, if preferred, instead of continuously in the same line.
- Of course it is desirable that the sleepers or anchoring devices shall be arranged transversely or at an angle to the direction of the 110 flooring in order to more securely fasten them in position, all within the spirit of the invention.
- Having thus fully described my invention, what I claim as new, and desire to secure by 115 Letters Patent, is—
1. An anchoring means for securing material to supporting-surfaces, comprising opposing gripping-walls and holding-flanges extending therefrom. 120
  2. A securing or anchoring means for holding materials to supporting-surfaces comprising opposing resilient walls and means for holding them with respect to each other, the space between the walls being arranged to receive fastening means projecting from the material which is to be secured in position. 125
  3. A floor anchoring or securing means, comprising sleeper-sections formed with web portions having nail-gripping walls and an- 130

choring-flanges projecting from the upper and lower edges thereof.

4. Anchoring means for flooring, comprising metal folded to form a double web with a nail-receiving space between its walls, and outwardly-extending flanges capable of being embedded in cement, concrete or other fireproof material.

5. An anchoring-sleeper for flooring, comprising metallic walls, shaped to form a corrugated hollow web and retaining flanges, the hollow webs receiving nails or other floor-securing means for fastening the flooring to said sleeper.

15. 6. A floor-anchoring means, comprising a section of metallic substance folded to form an anchoring-flange, a double corrugated web portion, and a floor-supporting flange.

7. A floor-anchoring sleeper, comprising metallic walls, forming a sleeper-web, outwardly-projecting flanges projecting from said walls adapted to be embedded in cement, concrete or the like and bolts or rivets for securing the walls of the webs in spaced relation to each other.

8. A floor-securing sleeper for fireproof structures, comprising a metallic section having opposing corrugated walls forming a nail or spike receiving space, the corrugated walls having a spring gripping action upon said nails or spikes, the upper edges of said walls being bent outwardly to form converging entrance-passages to the space between the walls of the webs.

35. 9. A floor-anchoring sleeper formed of a single piece of material bent and folded to form an anchoring-flange, the said material being then bent to form opposing walls and outwardly-extending flanges bent at the surface edges of the sleeper to receive and support the flooring, the web portion of the

50. sleeper accommodating and gripping floor-securing nails or spikes.

10. A floor securing and anchoring sleeper having opposed corrugated walls forming a body portion or web with a nail-receiving space therein, outwardly-bent edge portions at the top and bottom of the web portion forming anchoring-flanges, backwardly-folded flanges on one of said edges forming abutting strengthening portions to one of the anchoring flanged edges of the sleeper, backwardly-folded flanges at the other edge of the sleeper having their edges converging toward each other to produce a guiding entrance to the nail-space in the web of the sleeper.

11. A building-sleeper having a hollow, vertical, body portion inclosing a restricted space, the body portion having an open top and a closed bottom formed as a flanged or expanded, hollow base.

12. A building-sleeper having a hollow, vertical, body portion inclosing a restricted space, said body portion terminating at the top in a V-shaped or funnel configuration, 65 said body portion also having a closed bottom formed as a flanged or expanded, hollow base.

13. A building-sleeper having a hollow, vertical, body portion inclosing a restricted space, the body portion having an open top and a closed bottom formed as a flanged or expanded, hollow base; and rivets or bolts passed transversely through the body portion.

In testimony whereof I affix my signature in presence of two witnesses.

WILLIAM FRIBERG.
